(57) **CLAIM**

The ornamental design for a tape printing machine, as shown and described.

DESCRIPTION

FIG. 1 is a top view of a tape printing machine;

FIG. 2 is a front view thereof;

FIG. 3 is a right-side view thereof;

FIG. 4 is a left-side view thereof;

FIG. 5 is a rear view thereof; and,

FIG. 6 is a cross-sectional view taken along the line 6—6 of FIG. 1.

The broken lines depict environmental subject matter only and form no part of the claimed design.
